UNITED STATES PATENT OFFICE.

ALBERT TJEPKES, OF GRUNDY COUNTY, IOWA.

LOCKING MEANS FOR BARREL BUNGS AND FAUCETS.

Application filed May 21, 1927. Serial No. 193,237.

My invention relates to improvements in locking means for barrel bungs and faucets, and the object of my improvement is to furnish a locking means adapted to lock both the bung and the faucet of a barrel or other liquid container at the same time.

This object I have accomplished by the means which are hereinafter described and claimed, and which are illustrated in the accompanying drawings, in which Fig. 1 is a vertical central section taken through a barrel head and the sectional bung thereof, the faucet and other parts being shown in side elevation including my improved locking means for both the bung and faucet. Fig. 2 is an end elevation of the same elements, with parts of the barrel head broken away.

It is to be understood that modifications of the device herein illustrated may be made, and yet be covered by the scope of the appended claims.

My locking device is intended to simultaneously lock upon a container both the bung and a faucet thereof, to prevent either abstraction of a liquid by way of the faucet, or an unauthorized deposit of any liquid or other substance into the container by way of the bung.

1 is a barrel as positioned upon its side 30 with one head disposed vertically at 2, said head having in vertical alinement a bung-hole 3 and an outlet-port 4 below it. 5 is an interiorly threaded hollow bung-nipple in which is fitted the exteriorly threaded bung 35 6 having a closed outer end with an annular outer rib or widening 7. Projecting from this bung 6 is a hexagonal head for engagement by a wrench in the usual manner.

In the inlet-port 4 below is fitted an interiorly threaded sleeve-bearing, and the hollow exteriorly threaded stem 17 of a faucet 18 is mounted in this sleeve-bearing. Upon the upwardly projecting valve-stem of said faucet a downwardly troughed lever-crank 20 is pivoted on a pintle 19. The lever-crank has near its free end a longitudinal slot 16, medially disposed to receive therethrough a staple 21 fixed upon the faucet spout 22. The numeral 8 denotes a metal 45 plate whose body is annular and can be positioned in communication with the hollow of the sleeve bearing 5 concentrically and against its outer end. This plate 8 is shaped by bending or otherwise with parts 9 bent 50 at an angle to its body outwardly, one being

omitted at 11 for a purpose to be described, and in the structure illustrated the projections 9 are arranged to closely face and abut upon five of the hexagonal faces of the plug part 12, the gap at 11 spanning the sixth 60 face of the part or boss 12.

The projection 9 opposite the gap 11 has a transverse slotted aperture 10 just without the top of the boss 12. A locking-bar 13 has its upper end bent angularly at 14 65 and passed through the aperture 10 with the bar body 13 crossing and contacting with the top of the boss 12 and the bent part 14 engaging the abutting projection 9. In this position the bar 13 traverses the gap 11 70 and projects downwardly to have its lower terminal part 15 bent outwardly at a slight angle, this part 15 having a terminal longitudinal slot 16 which may receive the said fixed staple 21 therethrough. In this position, the looped catch 23 of a padlock may be 75 locked in the staple, so that the bar 13 securely lock both the bung 6 and also the faucet lever 20.

It will be understood that if the boss 12 80 is square or otherwise polygonal, the projections 9 of the plate 8 may be provided in number sufficient to perform the same function as those shown, by leaving a gap between two of the projections in line with 85 the apertured projection 9.

It should be noted, that when the padlock 24 has been removed and the bar 13 lifted away from the boss 12 to clear the side projections 9, that the bar may be detached 90 from the apertured projection. When the bar part 15 is separated from the faucet staple 16 the bar may be used as a wrench with which to turn the bossed plug 12-6 to remove it or replace it, engaging the projections 9 at each end of the gap 11.

Having described my invention, what I claim as new, and desire to secure by Letters Patent, is:

In a device of the character described, a 100 screw-plug, a threaded hollow tube upon which the plug is removably mounted, said plug having an annular flange abutting upon the end of the tube, an annular plate removably engaged between said tube end and 105 said annular flange, the plug having a polygonal central boss, and the annular plate having a plurality of projections directed angularly therefrom to abut upon the side faces of said boss, one adjacent pair of the 110

projections being spaced apart and a projection opposite their gap having a transverse slot, a locking-bar having one end bent angularly, said angular end being hingedly connected to and through said slotted projection and the bar traversing the gap between the opposite pair of spaced projec-

tions, and means for locking releasably the locking-bar to an operating member of a faucet to prevent operation thereof. 10

In testimony whereof I affix my signature.

ALBERT TJEPKES.
